UNITED STATES PATENT OFFICE.

FREDERICK KNAUST, OF BROOKLYN, NEW YORK.

METHOD OF CONSTRUCTING CEMENT WALLS.

Application filed May 29, 1925. Serial No. 33,595.

The present invention relates to improvements in wall construction and method of producing walls, particularly cement walls, and it is the principal object of the invention, to produce the wall of uniformly constructed units, anchored to one another.

Another object of the invention is the provision of a cement wall construction which requires no wooden parts and is equipped with inclined, pairwise arranged tubular reinforcing members, each pair of which is spaced from the other pair.

A further object of the invention is the provision of a cement wall construction formed of a plurality of uniformly constructed units, each comprising a centrally located resilient reinforcing member anchored to the sides of the wall structure.

A still further object of the invention, is the provision of novel and improved anchoring means for connecting one unit of the wall construction to the other.

These and other objects and advantages of the invention will become more fully known as the description thereof proceeds, and will then be specifically set forth in the appended claims.

In the accompanying drawing forming a material part of this disclosure:

30 Fig. 1 is a top plan view of a wall constructed according to the present invention and method.

Fig. 2 is a cross-section on line 2—2 of Figure 1.

35 Fig. 3 is a view similar to Figure 2, of a modified form of wall construction.

The wall construction comprises a bottom plate 10 horizontally disposed on which a horizontal tube 11 is placed and anchored thereto in any suitable manner. The two side walls 12 and 13, are preferably constructed from meshed wire or other suitable material, secured to the bottom plate in a convenient manner.

45 A plurality of angularly disposed, pairwise arranged tubular members 14 and 15, are anchored at their lower meeting ends by means of suitable anchoring means, such as, wires or cables 16 and 17, to the tubular

50 block 11 and have upper open ends on which collars 18, or the like, are mounted.

The pairs of inclined tubular members 14 and 15, in the wall construction, are suitably spaced from each other, as indicated in

55 Figure 1.

Cement 19, is poured between the two

wall members 12 and 13, to approximately half of the height of the same, and then a tube 20 of resilient material and of a form shown in Figure 2, is embedded into the cement, and is held in position by means of wires 21 and 22, the other ends of which are anchored in the side walls 12 and 13, in a suitable manner. Then the remainder of the space between the walls is filled with cement.

In this manner, one unit of the wall construction is prepared, and if it is desired to top the same by another, similarly constructed section, the base plate 23 of this section has placed thereon a horizontal tubular block 24, similar to tube 11, which, at its sides, carries hooks 25 and 26 adapted to be engaged by similar hooks 27 and 28, embedded in or secured to the upper ends of the tubular inclined members 14 and 15, of the lower unit.

The tubular, angularly disposed members 29 and 30, of this section, are anchored to the block 24 by wires or cables 31, and after this unit has been half filled with cement 32, another resilient tube 33, similar to member 20, is provided which is held in place by means of wires or cables 34 and 35, anchored at their outer ends, in the side walls, 36 and 37, of this unit.

In this manner, as many similarly constructed units may be added, one on top of the other, as desired, in order to construct walls of any desired height.

The modified form of wall construction 90 illustrated in Figure 3, is constructed in the same manner as described above, with the exception of the engaging hook members.

In the modified form, the tube 24 has secured therein or formed therewith, lateral 95 members 38 and 39, formed with recesses 40 and 41 adapted to be engaged by the toothed upper ends of members 42 and 43, the lower ends of which extend into the tubular members 14 and 15, and are anchored therein 100 by wires or cables 44 and 45, while springs 46 and 47, or the like, in said tubular members, have the tendency to pass the upper ends of members 42 and 43 in engagement with members 38 and 39.

The operation of the device and the method of constructing a wall according to my invention, will be entirely clear from the above description without further explanation.

It is to be understood that changes may be made in the construction of the wall and

in the steps of the method of making the same, such as fall within the scope of the appended claims without departure from the spirit and principle involved.

5 Having thus described my invention, what I claim as new, and desire to secure by Letters Patent, is:

- 10 1. A wall comprised of a plurality of units, each comprising a bottom plate, a pair of side walls thereon, a block on said bottom plate, inclined reinforcing members anchored to the bottom plate, a centrally located reinforcing tube, a means for anchoring said tube to the side walls, and a means for anchoring said inclined members to the unit next above.
- 20 2. A wall comprised of a plurality of superposed units, each comprising a horizontal bottom plate, a pair of wire mesh side walls erected on said plate, a tubular block on said bottom plate, inclined tubular reinforcing members resting on said block, cables for anchoring said members to said block, centrally located resilient reinforcing means in said unit, means for anchoring said reinforcing members to the side walls, and a means for anchoring said inclined members to the block on the bottom of the unit next above.
- 25

3. A wall construction including a plurality of superposed units, each comprising a bottom and side walls adapted to be supported by the unit underneath, a plurality of pairwise arranged, spaced, inclined reinforcing members, a block on said bottom to which said reinforcing members are anchored, a resilient tubular horizontal, centrally located reinforcing member adapted to be embedded into the cement filled between the walls, anchoring means for said inclined members, and anchoring means for said centrally located reinforcing member, and hooks attached to said inclined members, adapted to engage hooks on the block of the unit next above for firmly connecting two adjoining units.

4. In a wall construction of the character described the combination of two superposed, equally constructed units with means for anchoring one unit to the other, said means comprising pairwise arranged hook members on one unit adapted to engage pairwise arranged hook members of the other unit.

55 In testimony whereof I have affixed my signature.

FREDERICK KNAUST.
